UNITED STATES PATENT OFFICE.

FRANK L. JOBSON, OF RICHMOND, VIRGINIA, ASSIGNOR OF ONE-THIRD TO W. J. McAUGHEY,
OF RICHMOND, VIRGINIA.

INSULATING-TILE.

No. 919,175.

Specification of Letters Patent. Patented April 20, 1909.

Application filed May 27, 1908. Serial No. 435,249.

To all whom it may concern:

Be it known that I, FRANK L. JOBSON, a citizen of the United States of America, and a resident of Richmond, county of Henrico, 5 State of Virginia, have invented certain new and useful Improvements in Insulating-Tile, of which the following is a full and clear specification, reference being had to the accompanying drawings, in which—

10 Figure 1 is a cross section of one of the tile; and Fig. 2 is a vertical section of a wall constructed of tile made according to my invention.

The object of this invention is to provide a 15 heat-insulating tile and a method of making the same whereby the tile shall have a maximum degree of insulating capacity, as more fully hereinafter set forth.

The idea of the invention is to make the 20 brick or tile hollow and exhaust the air therefrom, thus converting the space into a vacuum, the insulating quality of which is well known. As much of the interior mass or body of the tile is removed as is possible 25 without rendering the tile liable to collapse by air pressure, and the walls of the tile are rendered permanently air-tight in a suitable manner.

The tile is made of suitable clay as usual. 30 When made of clay the walls are naturally somewhat porous even after baking, so in order to close all pores and render the walls air-tight I coat the outer surface of the walls with a thick glaze or other coating *a* after the 35 air is exhausted. The air may be exhausted in any manner. One of the walls of each tile may be provided with a small hole (as *b*) and the tiles exhausted while they are piled in the glazing oven, the oven being made-air- 40 tight and a suitable exhausting means being employed to exhaust the oven during the glazing operation, whereby each tile will be hermetically and permanently sealed by a coating which will fill all the pores of the 45 walls, as well as the escape opening *b*, and which will become a permanent and homogeneous part of the tile. It is evident that if the walls of the tile are sufficiently porous to permit the confined air to escape there- 50 through the special air-escape opening may

be dispensed with. It is also obvious that a loose plug may be placed in the opening *b* which will be sealed into place by the fusing and melting of the glaze, but it is believed that a sufficiently small opening may be 55 made that the glaze itself will plug it. Substantially the same result may be obtained by simply heating up a non-airtight glazing oven to a sufficiently high temperature to consume and drive out the air from the tile 60 and keep it out until the walls are made air-tight by the fusing of the glazing material and it is believed, inasmuch as the temperature employed for the glazing process is a very high one, that that temperature will be 65 sufficient for that purpose, whereby the tile will be exhausted to a practical degree and be rendered air-tight simply by the usual glazing operation.

It will be observed that a wall constructed 70 of my tile will possess a very high degree of non-conductivity and inasmuch as the units of which the wall is constructed are entirely independent the destruction of the vacuum in one will not affect the heat-resisting 75 qualities of the others. It will be observed also that instead of exhausting the tile in bulk, in either of the ways described, they may be individually exhausted and plugged after or during the glazing process. 80

Having thus fully described my invention, what I claim as new, and desire to secure by Letters Patent, is:—

1. An insulating tile or brick made of baked clay, said tile being made hollow and 85 its interior being exhausted of its air and the exterior of the tile being entirely coated with an air-impervious coating.

2. A hollow baked clay tile having the air exhausted from its interior to a rarefied condition, the exterior of the walls of the tile being provided with a continuous air-impervious glaze baked into the clay of the tile. 90

In testimony whereof I hereunto affix my signature in the presence of two witnesses 95 this 18 day of May 1908.

FRANK L. JOBSON.
